UNITED STATES PATENT OFFICE.

MAX BACHLIN, OF BROOKLYN, NEW YORK.

GUTTER HANGER.

Application filed November 13, 1925. Serial No. 68,837.

The present invention relates to improvements in gutter hangers for use with a gutter having a beaded edge.

One of the objects of the invention is to provide a gutter hanger including a bar extending transversely of the gutter and provided on one of its ends with a hook-shaped section fitting over the bead of the gutter, simple and efficient means being provided for causing a snug engagement of said hook-shaped section with said bead and for effectively locking the said hook-shaped section in position.

Another object of the invention is to provide a gutter hanger wherein the connection between the bar and the roof strap is made by a clip coupling, in combination with simple and efficient means for preventing movement of said roof strap in relation to said bar.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of the invention is illustrated in the accompanying drawings, in which:

Figure 1 is a side elevation of a gutter hanger constructed in accordance with the present invention, the gutter being shown in position thereon; Fig. 2 is a similar elevation of the hanger before it is applied to the gutter; Fig. 3 is a top plan view of the construction shown in Fig. 2; Fig. 4 is a section taken on line 4-4 of Fig. 2, on a larger scale; and Fig. 5 is a section taken on line 5-5 of Fig. 2, also on a larger scale.

In the drawings, the numeral 10 indicates a roof gutter, the outer edge of which is provided with a bead 11, as usual in devices of this type, while its inner edge 12, adjacent the wall of the building, is plain. For supporting the gutter in proper relation to the roof of the building, there is provided a plurality of gutter hangers, spaced apart

a suitable distance, each of said hangers including a bar section 13, which extends horizontally and transversely between the upper edges of the gutter, a strap 14 underlying the gutter, and a suspension or roof strap 15, attached to the bar 13 and to the roof.

The bar section 13 is of inverted U-shape in cross section from end to end, it including a top web 16 and side flanges 17. This bar is provided at one of its ends with a hook-shaped bend 18, fitting over the bead of the gutter, while its opposite end is bent over the plain edge of the gutter, as shown at 19. This last-mentioned section of the bar is provided with a transverse slot 20, for a purpose hereinafter to be described. The free end 21 of the hook-shaped bend 18 is arc-shaped, its curvature conforming to that of the body portion of the gutter 10 immediately below the bead 11. The longitudinal edges 22 of this arc-shaped section are bent inwardly toward one another, as clearly shown in Fig. 5 of the drawings, they embracing the strap 14 adjacent one of its ends. The end 14' of the strap 14 projects beyond the arc-shaped portion 21 and is adapted to be disposed in the bead 11 of the gutter, as clearly shown in Fig. 1 of the drawings. The other end of the strap 14 is adapted to be extended through the slot 20 and to be then bent downwards against the portion 19 of the bar 13. The connection between the strap 14 and the arc-shaped portion 21 of the gutter hanger is, preferably, made by forming in the portion 21 one or more projections 23, which are seated in recesses 24 in the strap 14. These projections and recesses are formed by means of a pointed tool, after the elements of the hanger have been assembled.

The roof strap 15 is in the form of a metal strip, the lower end of which is bent horizontally as shown at 25, the said horizontal portion being provided with downwardly extending flanges 26. The strap rests upon the top web 16 of the bar section 13, its flanges 26 being disposed in recesses 27 in the side flanges 17 of the bar section 13. Adjacent the outer ends of the flanges 26, the strap 15 is bent upwardly, as shown at 28, and adjacent the other ends of the said flanges, there is formed on the said strap an upwardly extending projection 29, co-operating with the upwardly bent portion 28 of the strap in a manner hereinafter to be described. The connection between the roof

strap 15 and the bar 13 is made by a clip 30, which straddles the roof strap 15 and the bar 13. This clip fits between the upwardly extending portion 28 and the projection 29 of the roof strap and is U-shaped in transverse cross-section. The free edges 31 of the side flanges 32 of the said clip are bent against the inner faces of the side flanges 17 of the bar 13. It will be noted 10 that, inasmuch as the clip 30 is disposed between the upwardly extending portion 28 and the projection 29 of the roof strap, the said clip cannot disengage itself from the said roof strap after the parts have been assembled. The roof strap, on the other hand, cannot move longitudinally on the bar section 13, because its flanges 26 are disposed in the recesses 27 in the side flanges 17 of the bar section 13.

20 At the juncture of the bar 13 and the hook-shaped bend 18 is formed a stiffening rib 33. This rib extends, preferably, across the juncture, as clearly shown in Figs. 1 to 3, inclusive, of the drawings, and serves to 25 insure proper bending of the hook-shaped portion into snug engagement with the bead of the gutter, as will hereinafter appear.

The operation of this device is as follows: First the end 14' of the strap 14, which projects beyond the arc-shaped portion 21, is 30 inserted into the gutter bead, and then the hook-shaped section 18 engaged with the said bead, by forcing the bar 13 downwards until the bent portion 19 on the free end of 35 the said bar is engaged with the plain edge 12 of the gutter. The end 14' of the strap 14 being disposed in the bead and a rib 33 being formed at the juncture of the hook-shaped section and the bar 13, a proper 40 bending of the said hook-shaped section and snug engagement thereof with said bead is insured when the bar section 13 is forced downwards against the plain edge 12 of the gutter. The strap 14 is then bent around the 45 gutter and extended through the slot 20 in the bar section 13. The free end of the strap

14 is then bent downwards into engagement with the bent portion 19, as clearly shown in Fig. 1 of the drawings. The free end 21 of the hook-shaped section 18 of the hanger is 50 arc-shaped to insure a snug fit thereof against the body portion of the gutter. It is to be noted that, since the end 14' of the strap 14 is disposed in the bead of the gutter, the hook-shaped section 18 is effectively 55 locked in position.

What I claim is:—

1. A gutter hanger including a channel bar extending transversely between the upper edges of the gutter, said bar being centrally provided in each of its side flanges with a recess, a roof strap having its lower end resting upon said bar and being provided with flanges seated in said recesses, and a clip straddling the lower end of said 60 roof strap and said bar and thereby holding said roof strap in position upon said bar.

2. A gutter hanger for use with a gutter having a beaded edge comprising a bar extending transversely of the gutter and provided at its outer end with a hook-shaped section fitting over the bead of the gutter, the opposite end of said bar being adapted to be fixed to the opposite edge of the gutter, the free end of said hook-shaped section 70 being channeled, a strap member designed to underlie the gutter, said strap member extending through the channeled end of said hook-shaped section and having an extension adapted for insertion into the beaded edge of the gutter, the other end of said strap member being adapted to be engaged with the opposite end of said bar, and co-acting projections and recesses on the channeled portion of said hook shaped section 80 and strap member for fixing said last-named two elements against longitudinal movement in relation to one another.

Signed at New York, in the county of New York, and State of New York, this 12th 90 day of November, A. D. 1925.

MAX RACHLIN.
